UNITED STATES PATENT OFFICE.

WILLIAM E. SMITH, OF MILLTOWN, NEW JERSEY, ASSIGNOR TO KILBOURN MANUFACTURING CORPORATION, OF NEW BRUNSWICK, NEW JERSEY, A CORPORATION OF NEW JERSEY.

CIRCULAR-KNITTING MACHINE.

1,227,683.

Specification of Letters Patent. Patented May 29, 1917.

Application filed July 6, 1916. Serial No. 107,737.

To all whom it may concern:

Be it known that I, WILLIAM E. SMITH, a citizen of the United States, residing at Milltown, in the county of Middlesex and 5 State of New Jersey, have invented certain new and useful Improvements in Circular-Knitting Machines; and I do hereby declare the following to be a full, clear, and exact description of the invention, such as will enable 10 others skilled in the art to which it appertains to make and use the same.

My invention consists in the novel features hereinafter described, reference being had to the accompanying drawings which 15 show one form in which I have contemplated embodying the invention selected by me for purposes of illustration, and the said invention is fully disclosed in the following description and claims.

20 Referring to the said drawings:

Figure 1 is a vertical sectional view of a portion of a circular knitting machine of the general character known in the art as the Kilbourn knitting machine, having my 25 invention embodied therein, the section being taken centrally through the knitting cylinder, and the plane of section extending substantially centrally with respect to the separate groups of needles which knit the 30 front and rear portions of the tubular fabric under the action of separate cams.

Fig. 2 is a similar section taken at right angles to the plane of section in Fig. 1.

Fig. 3 is a diagrammatic view of the upper cam cylinder as it would appear if cut 35 and spread out into a plane, parts being broken away.

Fig. 4 is a vertical section through the cam on the line 4—4 of Fig. 3.

40 Fig. 5 is a top plan view of the portion of the cam adjacent to the auxiliary vertically movable knitting cam.

Fig. 6 is a view similar to Fig. 3 showing the inner face of the lower cam cylinder as 45 it would appear if cut and spread out into a plane.

Fig. 6a is a detail view illustrating certain of the needle nibs.

Fig. 7 is a vertical sectional view on line 50 7—7 of Fig. 6.

Fig. 8 is a diagrammatic view representing the circular series of needles, and the knitting threads employed in knitting portions of the tubular fabric by circular knit-

ting for the purpose of increasing the length 55 of a segmental portion of the fabric.

Fig. 9 is a diagrammatic view representing one form of stocking knit by my improved machine.

Fig. 10 is a diagrammatic view illustrating 60 the circular series of needles, the knitting threads and the thread guides in perspective.

Fig. 11 is a partial diagrammatic view of a slightly modified form of stocking which 65 may be produced by my improved machine.

Fig. 12 is a view similar to Fig. 8 showing a slight modification of the invention.

Fig. 13 is a view similar to Fig. 3 showing 70 a modified form of cam.

Fig. 13a represents several forms of needle shanks or jacks provided with nibs of three different lengths for engaging the cam shown in Fig. 13.

Figs. 14 and 15 are vertical sections on 75 lines 14—14 and 15—15 respectively of Fig. 13.

Fig. 16 is a view similar to Fig. 6, showing a slight modification in the form of cam.

My invention relates to one form or embodiment of mechanism for carrying out the process and producing the fabric disclosed in my companion application filed July 6th, 1916, and given Serial #107,736, and has for

its object the production of a tubular seam- 80

less fabric knit by circular work, and comprising a plurality of circular courses of stitches knit by a continuous main knitting thread, and a partial course or partial 85

courses of stitches knit with a separate thread, each partial course lying between 90

portions of two adjacent circular courses and preferably having the ends of the thread forming each partial course knitted into 95

stitches of the adjacent circular courses of 100

stitches, the said partial courses extending through a segment only of the tubular fabric, and being of substantially the same gage as the stitches of the circular courses for the purpose of making such segmental portion 105

of the tubular fabric actually longer than the other portions not so provided with the partial courses.

In carrying out my present invention, which as before stated, relates to the mechanical means for carrying out the said process and producing the said fabric, I take 110

the well known Kilbourn knitting machine,

such a machine, for example, as is illustrated in Letters Patent of the United States #1,087,954 granted to E. E. Kilbourn, Wm. E. Smith, and I. W. Kilbourn, February 24th, 1914, and by making certain changes therein adapt it for the purpose of carrying my invention into effect as hereinafter fully explained, but I do not limit myself to the application of my invention to a Kilbourn knitting machine, as it may be applied to or embodied in other forms of knitting machines without departing from the invention.

Referring to the accompanying drawings, Figs. 1 and 2 represent vertical sections through the axis of the knitting cylinder of my improved machine which in its general structure corresponds to that of the well known Kilbourn type. 20 represents the needle cylinder provided with the usual needle grooves, and a circular series of needles indicated diagrammatically in Figs. 8 and 12. The group of needles, 1 and 1^a, lying on one side of the dotted line x—x in Fig. 8, are those employed for knitting the front part of the leg and the top of the foot of the stocking, and the group of needles, 2, extending on the other side of said dotted line, x—x, are those which are employed for knitting the rear portion of the leg of the stocking and sole of the foot during circular work, and for knitting the heel and toe pockets in a well known manner by reciprocating work and narrowing and widening, it being understood that the machine is provided with the usual narrowing and widening means provided in the Kilbourn knitting machine.

The two groups of needles, 1^a—1^a, of the first mentioned group represent a plurality of needles located adjacent to the needles, 2, on each side of the tube which are operated in a different manner from the needles, 1, as hereinafter described for the purpose of tying in the ends of the extra thread in knitting the inserted partial courses. The knitting cylinder is provided with sinkers, 21, of any usual or ordinary kind, in this instance, operated by a sinker ring, 22, and for actuating the needles, two cam cylinders are provided, to wit, an upper cam cylinder, 30, for actuating the needles, 2, during circular and also during reciprocating work, and the cam ring, 31, for actuating the needles, 1 and 1^a, during circular work, said needles remaining stationary during reciprocating work.

It will be understood that in knitting circular work the two cam rings, 30—31 are simultaneously rotated so as to operate all of the needles of the circular series while in knitting reciprocating work the cam ring, 31, remains stationary, and the cam ring, 30, only is reciprocated, suitable mechanism therefor being provided in the Kilbourn

knitting machine, which is, therefore, not herein shown and described.

In carrying out my invention, during each rotation of the cam rings, during circular work, when it is desired to insert partial courses heretofore referred to, I provide means for causing a group of the needles, in this instance, the group of needles, 2, after they have been actuated by their appropriate cam, to make their respective stitches forming part of the usual or normal circular course of knitting with the main knitting thread, to form a second stitch with a separate or extra thread during the formation of the circular course of knitting, and this operation may be repeated during any number of successive circular courses of knitting or at intervals in knitting a plurality of circular courses, as desired.

The upper cam cylinder, 30, which operates the needles, 2, is provided with the usual knitting cam, 10, and is also provided with an extra knitting cam indicated at 11 in Fig. 3, which, in this instance, follows the main knitting cam and causes each of the needles, 2, to be actuated a second time in each circular course, after they have been actuated by the usual knitting cam, 10, and restored to raised position. I also prefer to provide means for throwing the cam into and out of operative position so that it may be dispensed with, when it is desired to knit ordinary plain circular knitting, that is to say, a succession of circular knit courses. In this instance, I have shown the cam, 11, provided with a vertically movable portion, in a well known way, so that it can be depressed until its upper surface is flush with the upper edge of the cam groove, or a ledge, as indicated in dotted lines in Fig. 3. The auxiliary knitting cam, 11, may be moved into and out of operative position by hand or by mechanism under the control of the pattern wheel in a well known way. In this instance, I have shown the cam, 11, provided with an operating arm or projection, 11^a, extending outwardly from the cam ring, 30, adapted to be engaged by hand or operated by the pattern controlled mechanism as preferred, the cam, in this instance, being held in its adjusted position by frictional engagement with the adjacent portions of the cam ring, although it might be held in position in any other desired manner.

The lower cam cylinder, 31, is provided with the usual knitting cam, indicated at 12, for actuating the needles, 1 and 1^a, the ordinary riser grade of the cam being, indicated at 13. I prefer to tie in the ends of the extra thread forming each of the partial courses to prevent them from pulling out or to the surface of the fabric after the ends are severed, and for this purpose I prefer to provide for raising a plurality of the nee-

dles, indicated at 1^a, at each end of the group of needles, 2, into their normal raised positions before they would be raised by the riser grade in order that they may receive and hold the extra thread employed in knitting the partial courses and knit the same along with the main knitting thread in the next circular course of stitches. For this purpose, I provide the needles, 1, with short nibs, 1^b, while the needles, 1^a, are provided with longer nibs, indicated at 1^c, see Fig. 2, and I provide the cam ring, 31, with an extra riser cam, 14, in advance of the normal riser cam grade, 13, as clearly shown in Figs. 6 and 7, the riser cam grade, 14, having its face cut away so that it does not project toward the needle cylinder as far as the normal riser cam grade 13. It will thus be seen that the extra riser grade, 14, will engage the long nib needles, 1^a, and elevate them into their raised or thread receiving position before the short nib needles, 1, are elevated by the riser grade, 13.

In connection with the cam cylinders, I provide the main thread guide, indicated at 15, in Fig. 10, for feeding the main knitting thread, 3, which is operated in conjunction with the normal knitting cams, 10 and 12, of the cam cylinders during circular work, and I also provide an auxiliary thread guide, indicated at 16 in Fig. 10, for feeding the extra thread, 4, in conjunction with the extra cam, 11, of the cam cylinder, 30, for causing the needles, 2, to form the partial course of stitches with the thread, 4, during the formation of a circular course of stitches. The thread guide, 16, is movable into and out of operative position, in a well known way, and may be operated by hand or under control of the pattern mechanism.

I have not shown or described the specific mechanism for throwing the thread guide, 16, into and out of operative position, as such means for actuating the thread guides are well known in the art, and one form of such mechanism is shown, for example, in Letters Patent of the United States #669,730, granted to Edward E. Kilbourn March 12th 1901. For the purposes of the present invention such mechanism, for example, may be employed or the thread guide, 16, may be manipulated by hand.

Referring now to Figs. 8 and 10, I will describe the formation of a circular course of stitches with the main knitting thread, 3, and the simultaneous formation of a partial course of stitches of substantially the same gage with the extra thread, 4. In performing this operation both cam cylinders, 30-31, are rotated in conjunction with the main thread guide, 15, carrying the main knitting thread, 3, and the auxiliary thread guide, 16. As the thread guide, 15, delivers the thread, 3, to the needles, 1, they are actuated by the knitting cam, 12,

of the lower cam cylinder, 31, to form the stitch, and are restored to raised position by the normal riser grade, 13. Assuming that the cam cylinders revolve contra-clockwise, the thread guide, 15, delivers the main knitting thread to the needles, 1^a, which are also actuated by the cam, 12, to form stitches of the circular course, but these needles, having the longer nibs, 1^c, are quickly raised by the riser grade, 14, and at this point 70 the extra thread guide, 16, carrying the thread, 4, which, during the preceding portion of the revolution, has been in inoperative position inside of this circle of needles, is thrown out so as to commence delivering 75 the extra thread, 4, to the raised needles, 1^a. In the meantime, the thread guide, 15, has continued delivering the main knitting thread, 3, to the needles, 2, which are operated to form stitches of the circular course 80 by the main knitting cam, 10, in the usual manner, and are restored to elevated position when they receive the thread, 4, from the extra thread guide, 16, and are immediately actuated by the extra cam, 11, to 85 form additional stitches, said additional stitches forming a partial course, which will obviously intervene between two adjacent circular courses.

As the main thread guide, 15, passes from 90 the last of the needles, 2, it will deliver the main knitting thread to the needles, 1^a, on the other side of the needle cylinder and pass to the needles, 1, for the next successive circular course of stitches, the said 95 needles, 1^a, being quickly raised to their highest positions so as to receive the extra thread, 4, from the thread guide, 16, after it has passed the last of the needles, 2, when the extra thread guide, 16, is moved to inoperative position preferably within the circle of the needles and carries the extra thread, 4, across the cylinder to the needles, 1^a, on the opposite side during the first portion of the next rotation of the cam 100 cylinders, forming the float, 4^a, see Figs. 8 and 10.

The operation may be repeated as many times as desired and each rotation of the cam cylinders and their guides, as described, 115 will form a complete circular course, and also a partial course, the partial courses being confined to the group of needles, 2, and increasing the length of the segment of the fabric knit thereby beyond that of the 120 segment knit on the needles, 1, 1^a. It will be seen that while the extra thread, 4, is fed to the needles, 1^a, they do not thereafter draw a stitch until the thread guide, 15, has supplied them again with the main knitting thread, 3, when they draw the usual stitch and knit the same with the two threads, 3 and 4, thereby tying in the ends of the extra thread, 4, forming the partial course into the stitches of the next 130

adjacent circular course, so that when the floats, 4^a, are cut out, as indicated by the dotted lines 5 in Fig. 8, the ends will not work loose or be pulled to the surface of the fabric.

- 5 When it is desired to knit ordinary plain circular knitting the thread guide, 16, will be thrown out of operation or the thread, 4, broken, and the extra knitting cam, 11, will be thrown out of operation, as by depressing it, as indicated in dotted lines in Fig. 3, when the machine can be operated to make successive courses of plain knitting with the main knitting thread only.
- 15 In Fig. 9, I have illustrated one form of stocking which can be produced on my improved machine, and which is knit in the following manner. This stocking, being shown as a man's half hose, is provided with the usual rib top, indicated at A. The leg, B, is knit preferably by circular knitting, the two cam cylinders being rotated simultaneously and the auxiliary cam, 11, being thrown into inoperative position and the thread, 3, being supplied to the needles by the main thread guide, 15. I prefer to reinforce the courses of the leg immediately adjacent to the rib top, as indicated at b, in any desired way. After the leg of the stocking is knit down to the beginning of the heel, as indicated by the lines, 6, 7 and 8, and the high-spliced portion, F, of the leg immediately above the heel being reinforced, if desired, in any usual manner, the heel pocket, D, is knit by reciprocating work in the usual or any desired manner as by holding the cam ring, 31, stationary together with its associated needles and reciprocating the cam, 30, and throwing successive needles at each side of the group, 2, out of and into operation to produce the usual narrowings and widenings.

In knitting the foot of the stocking circular knitting is resumed with both cam cylinders rotated simultaneously and the thread, 3, being fed to all of the needles, as in knitting the leg. In order to give increased length to the sole portion C¹, so as to make it longer than the corresponding portion, C, of the top of the foot, I introduce a plurality of partial courses knit on the needles, 2, only, between adjacent circular courses by throwing the extra cam, 11, into operative position and feeding the extra thread, 4, by means of the movable thread guide, 16, to the needles, 2, and preferably also to the needles, 1^a, as hereinbefore described, the thread, 4, being floated across the tube from one side to the other, as hereinbefore described, the floats, 4^a, produced thereby being cut away after the stocking is finished.

The toe pocket, E, is then knit by reciprocating work in a manner similar to the heel pocket and subsequently connected to the

top portion of the foot by the usual toe joining, e. At the extreme end of the foot portion, I prefer to knit a few courses of plain circular knitting reinforced in any usual way to form a toe band, G, to facilitate the formation of the toe joining, but this forms no part of my invention.

I may knit the circular courses accompanied by partial courses at intervals, singly or in groups, in order to provide the desired extra length to the sole, or I may introduce a plurality of such combination courses at one point only, or at two or more points, as desired. For example, I may knit a plurality of successive circular courses adjacent to the heel, as indicated in Fig. 9, in each of which the needles, 2, are actuated by both cams, 10, and 11, to form two stitches while the needles knitting the top of the foot make only one stitch, as indicated at C², or I may form a plurality of such courses adjacent to the outer end of the foot portion, as indicated at C³, or I may form these courses at both ends of the foot portion, or in a group between the ends of the foot portion, or distribute them at intervals, as before stated, and this may be accomplished by throwing the cam, 11, and the thread guide, 16, out of and into operation according as it is desired to knit a plain circular course of stitches or a circular course accompanied by the partial course of the needles, 2.

It will be seen that I can introduce these partial courses at any point in circular knitting where they are desired and in Fig. 11, for example, I have shown a modified form of stocking in which these partial courses are introduced in the high-spliced portion above the heel for the purpose of giving increased length to the fabric at that point. While I prefer to have the auxiliary thread guide, 16, thrown out of operation by throwing it to the inside of the cylinder and floating the extra thread, 4, across the tube and to cut out the floats after the stocking is completed, it is within the scope of my invention to sever the extra thread, 4, after the completion of each partial course and reintroduce it on the other side of the tube in a well known way.

While I have shown the extra knitting cam, 11, as being located in rear of the normal knitting cam, 10, so that the partial course is knit on the needles, 2, after they have formed the stitches for the circular course it is within the scope of my invention to locate the extra knitting cam, 11, in advance of the normal cam, 10, so as to knit the extra course on the preceding circular course and follow it by the circular course knit on all the needles in the same revolution of the machine, the same being a mere reversal of the parts shown in the drawings.

In some instances, it may be desirable to insert the partial courses hereinbefore described through a narrower segment of the fabric than is shown in Fig. 1, for example 5 as in knitting a high spliced portion, which is narrower than the heel, or in knitting a sole portion in which the bottom portion is increased in length without carrying the partial courses up around the sides of the 10 foot to the ordinary lateral sutures. In such case, the needles knitting the partial courses would constitute only a section of the needles which knit the front half or rear half of the tube, the line of demarcation between which is indicated by the 15 dotted line α — α in Fig. 12.

In this figure, the needles, 1, represent those which knit the front of the leg of the stocking and the top of the foot, and 20 the needles, 2, 2^a and 2^b constitute the portions of the circular series which normally knit the back of the leg, the heel and toe pockets and the sole of the foot. In this instance, the partial courses are shown as 25 limited to the needles, 2, constituting a portion of this series of needles and the additional thread, indicated at 4^b, will be fed as hereinbefore described, preferably not only to the needles, 2, but also to a plurality of tying-in needles, 2^a, located at opposite sides of the group of needles, 2, the needles, 2^b, constituting the balance of the 30 needles of this half or series as clearly indicated in Fig. 12.

35 Under these conditions, I prefer to modify the cam which operates the needles, 2, 2^a and 2^b, for circular knitting so as to cause the formation of the partial courses as hereinbefore described, and preferably also to 40 raise the needles, 2^a, in advance of the needles, 2^b, to receive the extra thread, 4^b, and hold it until the next course of circular knitting with the main knitting thread, 3^a, so that the ends of the thread, 4^b, will be tied 45 in to the next circular course of stitches. This result may be accomplished in many ways, but I have shown, in this instance, an arrangement of cams suitable for use in the well known Kilbourn knitting machine 50 which I will now describe.

In carrying out this modification of the invention, I prefer to provide the needles, 2, with a longer cam engaging nib than those of the needles, 2^a and 2^b, the needles, 2^b, being provided with a short nib and the needles, 2^a, with what I term intermediate length nibs, which are longer than those of the needles, 2^b, and shorter than those of the needles, 2. The cam ring or cylinder, 30, 55 which is the upper cam cylinder of the Kilbourn knitting machine, is provided with a main knitting cam, 10^a, having the usual cam grade, 10^b, of such reduced thickness that it will engage only the needles, 2 and 2^a, and 60 raise them immediately, and I provide a

separate riser cam grade, 10^c, for raising the needles, 2^b, provided with the short nibs at a later period in the revolution of the cam cylinder. For knitting the intermediate partial course, I employ an auxiliary cam, 70 11^a, similar in all respects to the cam, 11, shown in Fig. 6, except that it is reduced in thickness so that it engages only the long nibs of the needles, 2, which may be of any desired number, and constitute a wider or 75 narrower segment of the tube, as preferred. The cam ring, which operates the needles, 1, to wit, the cam ring, 31^a, is illustrated in Fig. 16, and is provided with the usual knitting cam, 12^a, which operates all of the 80 needles, 1, as does the riser cam, 13^a.

In knitting the fabric, as shown in Fig. 12, it will be understood that the main knitting thread, 3^a, will be fed to the needles, 1, 2^b, 2^a, 2, 2^a and 2^b, passing around the cylinder in the direction of the arrow, for example, in Fig. 12, to make an ordinary course of knitting. During the knitting of this course, and after the main thread guide has commenced to deliver the main knitting thread to the needles, 2, the auxiliary thread guide, such for example as that indicated at 16 in Fig. 10, will introduce the extra thread, 4^b, delivering it first to the first group of tying-in needles, 2^a, which are 90 elevated by the riser cam grade, 10^b, after drawing their stitch with the thread, 3^a, before the needles, 2^b, adjacent thereto are raised. The extra thread, 4^b, is then fed to the tying-in needles, 2^a, the needles, 2, and the second group of tying-in needles, 2^a, which are likewise raised immediately after drawing their stitch with the thread, 3^a, and before the adjacent needles, 2^b, when the auxiliary thread guide will be moved out of 95 operative position and the extra thread will be floated across the cylinder as indicated at 4^c. These floats will be cut away after the fabric is completed as indicated at 5^a—5^a, and it will be seen that the end portions of 100 the thread, 4^b, fed to the tying-in needles, 2^a, will be knit together with the main knitting thread, 3^a, into the stitches of the next circular course. 105

While I have shown the extra cams, 11 and 11^a, herein as movable vertically into and out of operative position, it is within the scope of my invention to move these cams into and out of operative position in any desired way, as for example, by having the 115 said cams movable in a radial direction through the recess in the wall of the cam cylinder or otherwise, into and out of operative relation with the nibs of the needles actuated thereby.

120 It is also unnecessary in some cases to actuate the auxiliary thread guide for the purpose of throwing it into and out of operation with the needles, as in practice it will be found that by locating the auxiliary 125

thread guide in rear of the thread guide which delivers the main knitting thread, the auxiliary thread guide will pass the needles knitting the front of the leg and top of the foot while they are drawn down with the exception of the tying-in needles which receive the thread in the manner previously described and that, therefore, the auxiliary thread will be floated across the tube even if 10 the auxiliary thread guide remains at all times in operative position. The operation herein before described will, therefore, take place whether or not the auxiliary thread guide is alternately moved into and out of 15 operative position.

What I claim and desire to secure by Letters Patent is:

1. In a circular knitting machine, the combination with a circular series of needles, 20 stitch forming mechanism for actuating each needle once during circular work to produce plain knitting, and means coöperating therewith for feeding a main knitting thread circularly to all of said needles to produce successive circular contiguous courses of single 25 thread plain knitting, of means normally out of operative position, and capable of being thrown into operation for a partial course only, for separately feeding an extra 30 thread to a group of consecutive needles, and auxiliary stitch forming mechanism normally out of operative position for operating the needles of said group of needles only, a second time during the formation of a single 35 circular course of stitches with the main thread, to simultaneously form a partial course of plain knit stitches between said circular course and the next adjacent circular course.
- 40 2. In a circular knitting machine, the combination with a circular series of needles, stitch forming mechanism for actuating each needle once during circular work to produce plain knitting, and means coöperating therewith for feeding a main knitting thread circularly to all of said needles to produce successive circular contiguous courses of single 45 thread plain knitting, of means normally out of operative position, and capable of being thrown into operation for a partial course only, for separately feeding an extra thread to a group of consecutive needles, and auxiliary stitch forming mechanism normally out of 50 operative position for operating the needles of said group of needles only, a second time during the formation of a single circular course of stitches with the main thread, to simultaneously form a partial course of plain knit stitches between said 55 circular course and the next adjacent circular course, and means for throwing said auxiliary stitch forming mechanism and the said means for feeding the extra thread into and out of operative position.

3. In a circular knitting machine the combination with a circular series of needles, 65 stitch forming cam mechanism for actuating the same during circular work and means coöperating therewith for feeding a main knitting thread to all of said needles, auxiliary 70 stitch forming mechanism for imparting a second operation to a group of consecutive needles, during the formation of a single circular course of stitches with the main knitting thread, and means for feeding a separate thread to the needles of said group, and to adjacent needles located on opposite sides 75 of said group.

4. In a circular knitting machine the combination with a circular series of needles, 80 stitch forming cam mechanism for actuating the same during circular work and means coöperating therewith for feeding a main knitting thread to all of said needles, auxiliary 85 stitch forming mechanism for imparting a second operation to a group of consecutive needles, during the formation of a single circular course of stitches with the main knitting thread, and means for feeding a separate thread to the needles of said group, and to adjacent needles located on opposite sides 90 of said group, and means for elevating said adjacent needles in advance of the intervening needles not comprised in said group of needles, to facilitate feeding of said extra 95 thread thereto.

5. In a circular knitting machine the combination with a circular series of needles, 100 stitch forming mechanism comprising two cams for actuating a group of said needles twice in succession in each revolution of the machine, separate stitch forming cam mechanism for operating the other needles of the series once in each revolution of the machine, means for feeding a main knitting 105 thread to all of the needles during circular work, associated with said separate cam, and with one of the cams for said group of needles, and auxiliary means for feeding an extra thread to the needles of said group, 110 during a revolution of the machine, associated with the other cam for said group of needles.

6. In a circular knitting machine the combination with a circular series of needles, of a cam cylinder provided with two cams for actuating a group only of successive needles, twice in each revolution of the machine, a second cam cylinder provided with a cam for actuating all of the other needles, means 115 for effecting the operation of both cam cylinders during circular work, a main thread guide for delivering a main knitting thread to all the needles of the series, during circular work, in association with one of the cams of the first cam cylinder, and the cam of the second cam cylinder, and a separate thread guide for delivering a separate 120 125

thread to the needles of said group, in association with the other cam of said first cam cylinder.

7. In a circular knitting machine the combination with a circular series of needles, of a cam cylinder provided with two cams for actuating a group only of successive needles, twice in each revolution of the machine, a second cam cylinder provided with a cam for actuating all of the other needles, means for effecting the operation of both cam cylinders during circular work, a main thread guide for delivering a main knitting thread to all the needles of the series, during circular work, in association with one of the cams of the first cam cylinder, and the cam of the second cam cylinder, and a separate thread guide for delivering a separate thread to the needles of said group, and to adjacent needles on both sides of said group, in association with the other cam of said first cam cylinder, and means on one of said cam cylinders for elevating said adjacent needles in advance of the other needles operated thereby to receive the said separate thread.

8. In a circular knitting machine the combination with a circular series of needles, of a cam cylinder provided with two cams for actuating a group only of successive needles, twice in each revolution of the machine, a second cam cylinder provided with a cam for actuating all of the other needles, means for effecting the operation of both cam cylinders during circular work, a main thread guide for delivering a main knitting thread to all the needles of the series, during circular work, in association with one of the cams of the first cam cylinder, and the cam of the second cam cylinder, and a separate thread guide for delivering a separate thread to the needles of said group, and to adjacent needles on both sides of said group in association with the other cam of said first cam cylinder, said adjacent needles having longer nibs than the other needles not comprised in said group and said second cam cylinder being provided with a normal riser grade to elevate the short nib needles, and with a separate riser grade in advance of the normal riser grade for elevating the long nib needles to receive the said separate thread.

9. In a circular knitting machine the combination with a circular series of needles, of a cam cylinder provided with two cams for actuating a group only of successive needles, twice in each revolution of the machine, a second cam cylinder provided with a cam for actuating all of the other needles, means for effecting the operation of both cam cylinders during circular work, a main thread guide for delivering a main knitting thread to all the needles of the series, during circular work, in association with one of the cams of the first cam cylinder, and the cam of the second cam cylinder, and a separate thread guide for delivering a separate thread

series, during circular work, in association with one of the cams of the first cam cylinder, and the cam of the second cam cylinder, and a separate thread guide for delivering a separate thread to the needles of said group, in association with the other cam of said first cam cylinder, said last mentioned cam being movable into and out of operative position.

10. In a circular knitting machine the combination with a circular series of needles, of a cam cylinder provided with two cams for actuating a group only of successive needles, twice in each revolution of the machine, a second cam cylinder provided with a cam for actuating all of the other needles, means for effecting the operation of both cam cylinders during circular work, a main thread guide for delivering a main knitting thread to all the needles of the series, during circular work, in association with one of the cams of the first cam cylinder, and the cam of the second cam cylinder, and a separate thread guide for delivering a separate thread to the needles of said group, in association with the other cam of said first cam cylinder, said last mentioned cam being movable into and out of operative position.

11. In a circular knitting machine the combination with a circular series of needles, of a cam cylinder provided with two cams for actuating a group only of successive needles, twice in each revolution of the machine, a second cam cylinder provided with a cam for actuating all of the other needles, means for effecting the operation of both cam cylinders during circular work, a main thread guide for delivering a main knitting thread to all the needles of the series, during circular work, in association with one of the cams of the first cam cylinder, and the cam of the second cam cylinder, and a separate thread guide for delivering a separate thread to the needles of said group, in association with the other cam of said first cam cylinder, said separate thread guide being movable into and out of operative position.

12. In a circular knitting machine the combination with a circular series of needles, of a cam cylinder provided with two cams for actuating a group only of successive needles, twice in each revolution of the machine, a second cam cylinder provided with a cam for actuating all of the other needles, means for effecting the operation of both cam cylinders during circular work, a main thread guide for delivering a main knitting thread to all the needles of the series, during circular work, in association with one of the cams of the first cam cylinder, and the cam of the second cam cylinder, and a separate thread guide for delivering a separate thread

to the needles of said group, in association with the other cam of said first cam cylinder, said separate thread guide being movable into and out of operative position, and means 5 for throwing said last mentioned cam into and out of operation, whereby circular courses of stitches can be knit, with or without intervening partial courses.

13. In a circular knitting machine the 10 combination with a circular series of needles, of separate stitch forming mechanisms, each provided with a main knitting cam for operating a portion of said needles during circular work, one of said mechanisms being 15 provided with an auxiliary cam for operating a group of consecutive needles a second time in a single revolution of the machine, means for operating both of said stitch forming mechanisms during circular work, 20 means for feeding a main knitting thread to all the needles associated with a cam of each of said stitch forming mechanisms, and auxiliary means for feeding an extra thread to the needles of said group in association with 25 said auxiliary cam.

14. In a circular knitting machine the combination with a circular series of needles, of separate stitch forming mechanisms, each provided with a main knitting cam for operating a portion of said needles during circular work, one of said mechanisms being 30 provided with an auxiliary cam for operating a group of consecutive needles a second time in a single revolution of the machine,

means for operating both of said stitch forming mechanisms during circular work, means 35 for feeding a main knitting thread to all the needles associated with a cam of each of said stitch forming mechanisms, and auxiliary means for feeding an extra thread to 40 the needles of said group, and to tying-in needles at each side of said group, not actuated by said auxiliary cam, in association with said auxiliary cam.

15. In a circular knitting machine the 45 combination with a circular series of needles, of separate stitch forming mechanisms, each provided with a main knitting cam for operating a portion of said needles during circular work, one of said mechanisms being 50 provided with an auxiliary cam for operating a group of consecutive needles a second time in a single revolution of the machine, means for operating both of said stitch forming mechanisms during circular work, means 55 for feeding a main knitting thread to all the needles associated with a cam of each of said stitch forming mechanisms, and auxiliary means for feeding an extra thread to the needles of said group, and to tying-in 60 needles at each side of said group, not actuated by said auxiliary cam, in association with said auxiliary cam, and means for elevating the said tying-in needles, in advance of the adjacent needles on the side thereof 65 remote from said group of needles.

In testimony whereof I affix my signature.
WILLIAM E. SMITH.
